UNITED STATES PATENT OFFICE.

SANFORD C. BRADY, OF BARTLESVILLE, OKLAHOMA.

SEPARATOR ATTACHMENT FOR CISTERNS.

Application filed March 3, 1925. Serial No. 13,000.

To all whom it may concern:

Be it known that I, SANFORD C. BRADY, a citizen of the United States, residing at Bartlesville, in the county of Washington and State of Oklahoma, have invented certain new and useful Improvements in Separator Attachments for Cisterns, of which the following is a specification, reference being had to the accompanying drawings.

10 This invention relates to separator attachments for cisterns and more particularly to a device adapted to divert the first water coming from a roof or other surface to a sewer and subsequently to change the path 15 of water so that it passes to the cistern thus allowing for cleansing of the collecting surface before any of the water is passed to the cistern.

15 A further object of the invention is to provide a device of this character which may be very cheaply and readily produced and upon which the necessary repairs can be made at a very low cost.

20 A further object of the invention is to provide a device of this character including a tripping member into which water passes continuously during passage of water from the collecting surface, this tripping member being counter-balanced by a weight and 25 being so constructed that it automatically empties itself so that it assumes the proper position for directing water to the sewer between range without the necessity of mechanical setting.

30 A further object of the invention is to provide a device of this character which is self-draining as above described but which is so mounted and constructed that even though the rain slackens considerably, it will not 35 lose its function of maintaining the connection between the water from the collecting surface and the cistern.

40 A further object of the invention is to provide in a device of this character means for determining the amount of water passing to the counterbalance or actuator during that period expiring between the start of rainfall and the operation of the actuator to connect the supply with the cistern.

These and other objects I attain by the 50 construction shown in the accompanying drawings, wherein for the purpose of illustration is shown a preferred embodiment of my invention and wherein:—

Figure 1 is a perspective of a separator 55 attachment for cisterns constructed in accordance with my invention;

Figure 2 is a vertical sectional view therethrough;

Figure 3 is a section on the line 3—3 of 60 Figure 2; and

Figure 4 is a fragmentary section on the line 4—4 of Figure 2.

Referring now more particularly to the drawings, the numeral 10 indicates a casing 65 of any suitable form and having at its upper end an inlet 11 and at its lower end a pair of spaced outlets 12 and 13; the inlet as designated is attached for connection with the down-spout from a roof or other collecting surface while the outlet 12 is to be connected with a sewer or waste and the outlet 13 to the cistern. Within the casing and the upper end thereof is arranged a tray 14 having an opening 15 in the bottom thereof. 70 At the upper surface of the tray is arranged a removable screen 16 adapted to separate from the water such solids as twigs, leaves and the like which have formed upon the collecting surface (not herein shown) and 75 are brought down from this surface by the water. Access is had to the tray 14 and to the screen 16 so that this screen may be removed and cleansed by a hinged door 17 closing an opening 18 formed in the side 80 wall of the casing 10.

Extending vertically between the bottom of the tray 14 and the bottom of the casing 10 is a support 19 having pivotally connected therewith at vertically spaced points upper 90 and lower levers 20, 21. The lower lever 21 has pivotally connected with opposite ends thereof valves 22, 23 coacting with the outlets 12 and 13, these valves being substantially similar and each comprising a metal disk 24 having lugs 25 by means of which it may be pivotally engaged with the lever 21 and a packing disk or valve element 26 se-

cured to the disk 24 by securing elements 27. These securing elements serve to secure to the under surface of the packing disk a combined guide and disk holder 28 having 5 prongs projecting into the outlet to insure proper seating of the valve disk.

At one end, the lever 20 has formed thereon a yoke 29 embracing a tubular container 30 which is closed at its lower end, as at 31, 10 with the exception of a small leak port 32. The opposite end of the lever has adjustably secured thereto a balance-weight 33 of any suitable construction. Adjacent the balance-weight bearing end, the lever 20 is connected 15 with the lever 21 by a link 24. The balance weight is of such size that until a predetermined amount of fluid is collected within the container 30, movement of the lever 20 is prevented and the lever is maintained in 20 an inclined position as illustrated in full lines in Figure 2. When the lever 20 is in this position, the valve 23 is closed and the valve 22 open and the container 30 is so arranged that its open upper end 31 has 25 but a small portion thereof arranged beneath the opening 15 and accordingly but a portion of the water passing through this opening will enter the container. In order that the amount of water which does enter 30 the container while in this position may be regulated, I mount upon the under surface of the pan 14 a swinging gate 35 which may be swung to partially close that portion of the opening 15 above the mouth of the 35 container while in this position. In order that solids may be prevented from entering the container the mouth thereof is covered with a mesh 36 sufficiently fine to prevent entry into the container of any solids sufficiently large to clog the leak outlet 32.

When a sufficient amount of fluid has collected within the container 30, the container overbalances the weight 33 and moves downwardly to the position shown in dotted lines 45 in Figure 2. When in this position, its mouth is squarely opposed to the opening 15 and substantially all of the water passing through this opening falls into the container. At this time, the valve 22 is closed and the 50 valve 23 open.

In the operation, assuming rain to have started and the water to have begun flow through the inlet 11 into the casing, it will 55 pass through the opening 15 and a portion of the water so passing will enter the container 30, this portion being controlled by the position of the gate 35. At this time, the valve 23 being closed, the water passing through the casing is being directed through 60 the outlet 12 to the sewer or waste carrying with it any collected dust or débris from the receiving surface. The level of the water within the container 30 will gradually rise and finally reach a point in weight where it 65 will overbalance the counterweight 33 caus-

ing the container to move downwardly and the lever 20 to operate to shift the valves 22 and 23 so that the water is deflected to the cistern. It will be obvious that the time elapsing between the beginning of a flow 70 through the casing and its direction to the cistern will be controlled by an extent of the downpour, the position of the gate 35 and the size of the opening 32. One of these elements is, of course, beyond human control. The two remaining elements, the gate and vent may be so regulated that it is assured that the collecting surface is thoroughly washed before any water is directed to the cistern. After the casing 30 once reaches its lowest position and is arranged directly below the opening 15, it will be obvious that a slackening of the flow as from slackening of the downpour will not operate to cause the return of the container to its 80 raised position for since substantially all of the water passing through the casing is impinging upon the open mouth of this container, the flow would have to be extremely small to be of less extent than the flow from the container through the vent 32 and this is necessary to any decrease in the contents of the container. The gate 35 and those portions of the mechanism lying beneath the tray 14 may be inspected, removed or adjusted through an opening 37 formed in the side wall of the casing and covered by a removable sliding door 38.

Since it will be obvious that the structure hereinbefore set forth is capable of a considerable range of change and modification without materially departing from the spirit of my invention, I do not limit myself to such specific structure except as hereinafter claimed.

I claim:

1. In a separator attachment for cisterns, a casing having an inlet opening and a pair of outlets, valves controlling said outlets and connected for opposite operation whereby one of the valves opens as the other valve closes and operating mechanism for said valves including a counterbalanced container having a leak port whereby it is normally empty and of insufficient weight to overbalance its counterweight, said container when overbalanced by the counterweight only partially underlying said inlet opening to receive water passing therethrough and after overbalancing its counterweight receiving substantially all of the water passing through said opening.

2. In a separator attachment for cisterns, a casing having an inlet opening and a pair of outlets, valves controlling said outlets and connected for opposite operation whereby one of the valves opens as the other valve closes, and operating mechanism for said valves including the counterbalanced container having a leak port whereby it is nor-

5 mally empty and of insufficient weight to overbalance its counterweight, said container when overbalanced by the counterweight only partially underlying said inlet opening to receive water passing therethrough and after overbalancing its counterweight receiving substantially all of the water passing through said opening, and a gate for reducing the effective area of that 10 portion of the inlet beneath which the container is arranged when in the first named position.

15 3. In a separator attachment for cisterns, a compartment having an inlet and two outlets, a lever pivoted intermediate its ends within the compartment and having valves at opposite ends thereof for coaction with said outlets, a second lever pivoted within the compartment provided at one end with a 20 counterweight and at the opposite end with a container arranged beneath said inlet, the container having a leak and when empty being of insufficient weight to overbalance the counterweight of the last named lever, said 25 container when positioned under the influence of the counterweight having its mouth only partially underlying the inlet to receive water passing therethrough and when positioned by its own weight substantially 30 completely underlying said inlet to receive water passing therethrough and a connection between said levers for transmitting motion from one to the other thereof.

35 4. In a separator attachment for cisterns, a compartment having an inlet and two outlets, a lever pivoted intermediate its ends within the compartment and having valves at opposite ends thereof for coaction with said outlets, a second lever pivoted within 40 the compartment provided at one end with a counterweight and at the opposite end with a container arranged beneath said inlet, the container having a leak and when empty being of insufficient weight to overbalance 45 the counterweight of the last named lever, said container when positioned under the influence of the counterweight having its mouth only partially underlying the inlet to receive water passing therethrough and when positioned by its own weight substantially 50 completely underlying said inlet to receive water passing therethrough, a connection between said levers for transmitting motion from one to the other thereof, and a 55 gate associated with the inlet opening for partially closing that portion of the inlet opening overlying the mouth of the container when in the first named position.

60 5. In a separator attachment for cisterns, a casing having an inlet and a pair of outlets, valves controlling said outlets and connected for opposite operation whereby one of the valves opens as the other closes, and operating mechanism for said valves including a container normally positioned to re-

ceive a portion of the water passing through the inlet, said container having a leak and shifting after a predetermined amount of water has collected therein to a position where it receives from the inlet a greater 70 proportion of the water passing therethrough and a connection between said container and the valves whereby the positions of the valves are reversed as the container shifts. 75

6. In a separator attachment for cisterns, a casing having an inlet and a pair of outlets, valves controlling said outlets and connected for opposite operation whereby one of the valves opens as the other closes, and operating mechanism for said valves including a container normally positioned to receive a portion of the water passing through the inlet, said container having a leak and shifting after a predetermined amount of 80 water has collected therein to a position where it receives from the inlet a greater proportion of the water passing therethrough, a connection between said container and the valves whereby the positions of the valves are reversed as the container shifts, and means for regulating the amount of water passing through the inlet which is delivered to the container while in the first 85 named position. 90

7. In a separator attachment for cisterns, a casing having an inlet and two outlets, a support within the casing, a pair of levers pivoted to the support and each pivoted intermediate its ends, a link connecting the levers for simultaneous movement, a pair of valves carried by opposite ends of one of said levers and alternately coacting with said outlets to close the same, a weight normally maintaining one of said valves in engagement with its outlet and a container carried by the second lever and having a drain leak port, said container being normally positioned to receive a portion of the water passing through said inlet into the casing and when full shifting and thereby shifting the valves, said container when full assuming a position beneath the inlet wherein it receives a greater percentage of the water passing through the inlet than is received thereby 110 when in the first named position. 115

8. In a separator attachment for cisterns, a casing having an inlet and two outlets, a support within the casing, a pair of levers pivoted to the support and each pivoted intermediate its ends, a link connecting the levers for simultaneous movement, a pair of valves carried by opposite ends of one of said levers and alternately coacting with said outlets to close the same, a weight normally maintaining one of said valves in engagement with its outlet, a container carried by the second lever and having a drain leak port, said container being normally positioned to receive a portion of the water pass- 120 125 130 135

ing through said inlet into the casing and when full shifting and thereby shifting the valves, said container when full assuming a position beneath the inlet wherein it receives a greater percentage of the water passing through the inlet than is received thereby when in the first named position, and a gate

pivoted to the casing wall and swingable to partially close that portion of the inlet beneath which the container is arranged in the first named position. ¹⁰

In testimony whereof I hereunto affix my signature.

SANFORD C. BRADY.
